Be it known that I, PIERRE E. GUERIN, of the city, county, and State of New York, have invented a new and original Design for Lamp-

H are legs; J, dolphins' heads on the lower ends of the legs; K, scrolls resting against the enlarged bottom
15 part, F, of the column, and L scrolls extending from the top part of the legs H up to the collar D, adjacent to that part of the column below the collar D.

In testimony that I claim the foregoing as my invention I have signed my name in presence of two witnesses.
